UNITED STATES PATENT OFFICE.

MATHEW F. BIERSDORF, OF LOS ANGELES, CALIFORNIA.

AUTOMATIC SAFETY GATE-CLOSING DEVICE FOR FREIGHT-ELEVATORS.

1,229,019.

Specification of Letters Patent.

Patented June 5, 1917.

Application filed January 11, 1917. Serial No. 141,792.

To all whom it may concern:

Be it known that I, MATHEW F. BIERSDORF, a citizen of the United States, residing at Los Angeles, in the county of Los Angeles and State of California, have invented new and useful Improvements in Automatic Safety Gate-Closing Devices for Freight-Elevators, of which the following is a specification.

10 This invention relates to elevator gates and particularly pertains to locking means therefor.

It is common practice to supply freight elevators and some other classes of elevators with vertically sliding gates which are counter-balanced and require manual operation to raise them in order to open the elevator shaft. It sometimes happens that these gates are inadvertently closed while 20 the car is at a given floor and this causes considerable inconvenience. It is the principal object of this invention to provide locking means which will automatically act to maintain the gate in an opened position 25 at such a time and to further insure that the gate will automatically gravitate to its closed position when the elevator car leaves the floor.

Another object of this invention is to provide a simple locking device which may be directly actuated by the elevator car to engage or disengage the gravity weight provided the elevator shaft gate.

Another object is to provide a gate weight 35 of special construction so that it may be encountered by the locking mechanism and be held against upward movement.

Another object is to provide a locking mechanism which may be embedded within 40 the wall of the elevator shaft and is thus not liable to become inoperative.

Another object is to provide simple means for oiling the various movable parts of the gate and locking mechanism.

45 It is a further object to provide an elevator gate lock which is constructed of few parts and which may be readily adjusted to adapt itself to variation in the alinement of the locks at the different floors of the building.

Other objects will appear hereinafter.

The invention is illustrated, by way of example, in the accompanying drawings in which:

55 Figure 1 is a view in vertical elevation

and section as seen through the elevator shaft wall and as illustrating the manner in which the lock is actuated to secure the gate against downward movement.

Fig. 2 is a fragmentary view in vertical section and elevation illustrating the elevator gate and further disclosing the manner in which it is counterweighted.

Fig. 3 is a view in end elevation illustrating the elevator lock as disassociated from its mounting.

Fig. 4 is a view in side elevation illustrating the lock with one of its side plates removed to more clearly disclose its operating mechanism.

Fig. 5 is a view in end elevation illustrating the face plate of the lock and the lock bolt projecting therethrough.

Fig. 6 is a view in side elevation drawn on an enlarged scale and illustrating a means by which the lock may be adjusted to be aligned with the actuating cam.

Fig. 7 is a view in section illustrating the manner in which access is obtained to the weight well.

Referring more particularly to the drawings, 10 indicates an elevator car adapted to be vertically moved by a suitable hoisting mechanism. This car travels along a vertical elevator shaft 11 which is provided with a series of shaft openings or doorways 12, one of which is at each of the floors and adapted to be communicated with by the elevator. The shaft openings are closed by a vertically moving gravity operated safety gate 13 which is suspended from a hanger rope 14 which is fastened to the center of the gate and leads over a centrally disposed pulley-wheel 15 fixed at the top of the doorway. The rope is led from the pulley 15 to one side of the doorway and downwardly over a second pulley 16 into a weight well 17 where it is secured at the upper end of a counterweight 18. This weight may be formed either with circular or rectangular cross section and is secured to the rope 14 by a metallic fitting 19. This fitting is formed with rolled side flanges which extend horizontally and are adapted to be engaged by the locking device 20. In order to permit access into the well 17 a removable door or side 17' is provided as shown in Fig. 7.

The locking device is composed of an outer housing or case 21 which is rectangular

lar in shape and is formed with outwardly extending ears 22 and 23 which permit it to be securely fastened within a pocket in the elevator shaft wall and to communicate with the weight well as well as the elevator shaft. A front plate 24 is formed on the casing and has an opening 25 through it adapted to permit horizontal reciprocation of a locking dog 26 which is actuated by a mechanism within the housing. This dog is mounted upon a pivot pin 27 extending through the substantially vertical leg of a bell crank 28, the other leg of said crank extending substantially horizontal and actuated by a roller plate 29. The bell crank is mounted upon a pivot pin 30 and is secured to the roller plate by means of a sliding pin 31. The roller plate is substantially triangular in shape and has its pivot pin 32 disposed at the apex of the triangle. A portion of the plate extends outwardly from the housing through a slotted opening 33 and is formed with a horizontally extending slot 34 adapted to receive an adjustable shaft 35 upon which the roller 36 is mounted. This roller extends outwardly into the elevator shaft and is adapted to be encountered by a face cam 37 formed upon the elevator car and extending outwardly in a manner to move the roller inwardly toward the housing.

As a means for insuring that the pulleys 15 and 16 are suitably lubricated, a pair of superimposed oil reservoirs 38 are provided and fitted with communicating passages which lead to the shafts upon which the pulleys rotate and thus constantly supply them with lubrication.

When the locking device is to be used, it is mounted within the wall pocket and adjusted so that the roller at each floor will encounter the face cam 37 upon the car. This is done by moving the roller shaft horizontally along the slot 34 in the roller plate and thereafter locking it with a lock-nut 39. In case other adjustment is necessary, the shaft 35 may be extended, as illustrated in Fig. 6, so that the roller 36 will be positioned at any desired lateral point in the path of travel of the cam 37. When the level of the elevator car approaches the level of the floor, the face cam 37 will encounter the roller 36 and swing the roller plate 29 inwardly upon the pivot pin 32. This in turn will cause the pin 31 to be moved along a slot 31' in the roller plate. Movement of the pin 31 will act to swing the lever 28 in the direction of the arrow —a— and upon its pivot pin 30. This will cause the locking dog 26 to swing outwardly, as indicated in dotted lines of Fig. 4, and in the path of travel of the flange upon the weight fixture 19. When the elevator is brought to a stop, the dog will thus be extending outwardly into the weight

well. The elevator gate is then manually lifted and this will cause its counterweight 18 to move downwardly in the weight well. As the counterweight passes the dog 26 the dog will be swung downwardly so that it will permit the passage of the weight, after which it will act by gravity to swing outwardly into the position indicated in Fig. 1 of the drawings. When in this position the shank 26' of the dog will engage stop 75 pin 40 upon the roller plate, thus preventing the dog from swinging upwardly and permitting the weight to move out of its locked position. It will thus be seen that when the weight is engaged by the dog, as 80 illustrated in Fig. 1 of the drawings, it will be impossible for the gate to be drawn down and this can only be effected when the elevator has moved away from the floor. This will cause the face cam 37 to relieve the 85 roller 36 and permit a spring 41 to restore the various parts of the mechanism to their normal position of disengagement. When this has been accomplished the gate will move downwardly to its closed position, due to gravity, as its weight is slightly greater 90 than that of the counterweight.

It will thus be seen that the locking mechanism here disclosed is decidedly simple in its operation and is so constructed as to be 95 positively actuated by movement of the elevator car only, and in a manner to effectively lock the elevator gate in its opened position and to automatically permit the gate to close when the car has left the floor. 100

While I have shown the preferred construction of my elevator gate lock as now known to me, it will be understood that various changes in the combination, construction and arrangement of parts may be 105 made by those skilled in the art without departing from the spirit of my invention.

I claim:

1. The combination with an elevator gate having a counterbalancing weight, of a 110 lock adapted to be operated by the elevator for locking the weight down and holding the gate up, said lock comprising a housing adapted to be mounted in a pocket in the elevator shaft wall adjacent the weight well, 115 a bell crank pivotally mounted in the housing, a locking dog pivotally mounted to one leg of the bell crank and adapted to swing through the wall of the housing into the weight well and hold the weight from 120 going up, a roller plate pivotally mounted in the housing and carrying a pin for slidingly engaging the other leg of the bell crank and extending through the opposite side of the housing from the locking dog, a 125 roller carried by the outer end of the roller plate, and a cam upon the elevator for engaging the roller; so that when the elevator is in position with the cam in engagement with the roller, with the gate elevated and 130

the weight down, the locking dog will hold the weight down and hold the gate elevated.

2. In a lock for elevator gates, a housing, 5 a bell crank pivotally mounted in the housing, a locking dog pivotally mounted to one leg of the bell crank and adapted to extend through the wall of the housing, a spring connected to the bell crank and the housing 10 for withdrawing the locking dog, a roller

plate pivotally mounted in the housing and extending through the opposite wall from the locking dog, a pin carried by the roller plate and engaging the other leg of the bell crank, and a roller adjustably connected to 15 the roller plate and projecting outwardly from the housing.

In testimony whereof I have signed my name to this specification.

MATHEW F. BIERSDORF.
